(57) **CLAIM**

The ornamental design for a fluid emitting device, as shown and described.

DESCRIPTION

FIG. 1 is a front, right side, top perspective view of a fluid emitting device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a reference perspective view thereof, showing a state in which a cover is attached; and,

FIG. 9 is a reference view thereof, showing a state in which this article is placed in a loading stand.

The broken lines are included for the purpose of illustrating the environmental structure and form no part of the claimed design.

1 Claim, 9 Drawing Sheets
